UNITED STATES PATENT OFFICE.

WALTER P. MURPHY, OF NEW YORK, N. Y.

RAILWAY-CAR UNDERFRAME.

1,347,964.

Specification of Letters Patent. Patented July 27, 1920.

Original application filed August 3, 1916, Serial No. 112,889. Divided and this application filed November 7, 1917. Serial No. 200,703.

To all whom it may concern:

Be it known that I, WALTER P. MURPHY, a citizen of the United States, residing at New York city, in the county of New York and State of New York, have invented certain new and useful Improvements in Railway-Car Underframes, of which the following is a specification.

My invention relates to certain improvements in the construction of under frames 10 for railway cars, more particularly freight cars.

The draft arms of railway cars are subject to lateral stresses tending to break them 15 or tear them from their attachments. For example, the pressures and stresses against the follower plates of the draft rigging are likely to cause these parts to become bent to a greater or less extent. If bent to any 20 appreciable extent the follower plates have a wedging action against the cheek castings tending to spread the same, thereby exerting a lateral stress upon the draft arms.

It is one of the objects of my invention to 25 provide a draft arm of novel and improved construction, which can be used either on new cars or in the repair of old cars, more particularly cars having wooden under frames, and which will be light in weight, 30 relatively inexpensive to manufacture and at the same time extremely strong and rigid so as to be capable of withstanding the lateral stresses above mentioned, also the vertical stresses resulting from the up and 35 down movements of the couplers and such longitudinal thrusts as the draft sill must take under the buffing movements of the coupler.

A further object of the invention is to 40 provide an improved metal reinforcement for the center sills of a freight car having an under frame of wood construction, which will effectually prevent the sills from being broken, injured or loosened from their attachment to the car by the inertia shocks 45 and other destructive forces to which these members are subjected when the car is in service, and will furnish a rigid structure to which the draft arms may be attached.

The invention consists in the novel constructions, arrangements and devices to be 50 hereinafter described and claimed, for carrying out the above stated objects, together with other improvements relating to the construction of railway car under frames which

will be referred to in the following description.

This application is a division of my co-pending application Serial No. 112,889, filed August 3, 1916.

The invention is illustrated in certain preferred embodiments in the accompanying drawings, wherein:

Figure 1 is a plan view of a portion of the under frame and draft rigging of a 60 railway car of wood construction illustrating one form of the invention but with certain parts omitted for the purpose of making more clear the illustration of other features.

Fig. 2 is a broken longitudinal sectional view of this embodiment of the invention, showing the parts omitted from Fig. 1, but omitting the coupler draw bar, follower plates and cheek castings.

Fig. 3 is a cross-sectional view on line 3—3 of Fig. 2.

Fig. 4 is a view, in perspective, of one of the cheek castings.

Fig. 5 is a longitudinal sectional perspective of the parts shown in Fig. 3.

Fig. 6 is a view, in perspective, of one of the attaching angles used in the construction shown in the preceding figures.

Fig. 7 is a similar view of a brace for 85 the car bolster.

Like characters of reference designate like parts in the several figures of the drawings.

Referring to the drawings which show fragmentarily the end of the under frame 90 of a railway car constructed largely of wood, with a structure embodying one form of my invention applied thereto, 25 designates the end sill of the car, 26, 26 the center sills, 27 the dead wood, preferably provided with a striking plate 28, 29 the flooring of the car, and 30 a steel end, the lower edge of which is flanged at 31 so that it intervenes between the end sill 25 and the flooring boards 29. The under frame shown 100 in these figures comprises a metal I-beam body bolster 32. 33 is a coupler draw bar, 34 the yoke or spring casing, and 35, 35 follower plates. It will be understood that the draft rigging forms no part of my invention. 105

For the purpose of completely illustrating my invention, I have shown a form of draft rigging of familiar type in place between the draft arms. This device will not 110

require description in detail and it will be understood that the construction and arrangement constituting my invention are adaptable, with possible slight modifications 5 well within the scope of ordinary mechanical skill, to any of the draft riggings now in use on railroad cars. It will also be understood that details of construction of the parts of the under frame above referred to 10 might be modified without departure from the invention which is adaptable to various types of under frame.

Instead of the wood or cast metal draft arms heretofore employed, I provide a pair 15 of pressed steel draft arms 36, 36 formed with longitudinally extending corrugations 37 and preferably with outturned stiffening flanges 38 at their lower edges to which are secured the usual carry iron 39 and tie plate 20 40. Secured to the draft arms are cheek castings 41 (Fig. 4) consisting, in each case, of a longitudinally disposed plate 42 and a transversely disposed plate 43 against which the follower plate 35 of the draft rigging 25 bears. The plate 43 is formed with curved projections 44 which enter into the corrugations 37 of the draft arm. 45, 45 are stiffening webs on the inner sides of plate 42 and 46 are similar webs on the outer sides of the 30 casting, the latter webs lying within corrugations 37.

Preferably the draft arms are formed with horizontally extending portions 47 which lie 35 flatwise against the under sides of the center sills 26 and are secured thereto by bolts 48. The draft arms are also provided, preferably, with extensions 49 offset from the lower portions of the draft arms, formed 40 preferably with longitudinally extending corrugations 50 and secured to the inner sides of center sills 26 by bolts 51. This arrangement gives the draft arms very firm and reliable anchorage and also serves to reinforce the center sills against their tendency 45 to buckle out under the inertia shocks which the under frame of a car receives in service. To further reinforce and strengthen the center sills a channel-shaped member 52, formed with longitudinal corrugations 53, 50 is disposed in inverted arrangement between the center sills 26 and secured to the sills by the bolts 51. Preferably a corrugated plate 54 is riveted to the channel member 52 above the body bolster 32. It will be seen that the 55 upper portions of the draft arms, taken in conjunction with the member 52, provide a hollow truss or reinforcement for the center sills which will keep them in line and prevent them from being broken or torn 60 from their attachments.

The inner ends of the draft arms 36 are secured to the body bolster by angle plates 55. The outer ends of the draft arms are secured by angle plates 56 (Fig. 6) to the 65 under sides of the end sill 25 and dead wood

27; 57 are angles which limit the opening through which the coupler draw bar passes.

In order to brace the body bolster and further reinforce the center sills I provide bracing members 58 (Fig. 7) secured to the 70 center sills and formed with projections 59 bearing against the web of the bolster and attached thereto by angles 60. The lower edges of the brace members are formed with out-turned stiffening flanges 61. 62 is a 75 pressed steel cross brace arranged against the end sill 25 and extending from one draft arm to the other. 63 is an angular cross brace above member 62.

While I have described my invention in 80 certain preferred embodiments, it will be understood that modifications in the details of construction and arrangement might be made without departure from the invention. Therefore I do not wish to be understood as 85 limiting the invention to the precise constructions and arrangements shown except so far as certain of the claims are specifically so limited.

I claim:

1. In combination with the center sills of a railway car, a pair of sheet metal draft arms longitudinally corrugated and arranged under said center sills and formed with inwardly projecting offsets which 95 overlap and are secured to the inner sides of the center sills, said offsets being formed with longitudinal corrugations.

2. The combination with the wood center sills of a railway car, of a reinforcing structure comprising a steel plate formed with longitudinally extending corrugations and arranged between and secured to said center sills.

3. The combination with the wood center 105 sills of a railway car, of a reinforcing structure comprising a metal sheet formed with pressed longitudinally extending rigidifying corrugations and arranged between and secured to said center sills, and a pressed 110 steel, longitudinally corrugated draft arm secured to said sills and reinforcing structure.

4. The combination with the wood center sills of a railway car, of a reinforcing structure comprising a steel plate formed with pressed, longitudinally extending corrugations and arranged between and secured to 115 said center sills, and metal draft arms secured to said sills and reinforcing structure.

5. The combination with the end sill, bolster and center sills of a railway car, of a reinforcing structure comprising a metal sheet formed with pressed, longitudinally extending rigidifying corrugations and lying between and secured to the center sills, and longitudinally corrugated pressed 125 steel draft arms secured at opposite ends to the end sill and bolster, respectively, and 130

provided with upward extensions secured to said center sills and reinforcing structure.

6. The combination with the center sills of a car underframe of wood construction, of a sheet metal reinforcing structure which extends lengthwise of the car between and secured to said center sills, and which is provided with a plurality of longitudinal

10 corrugations.

7. The combination with the center sills, end sill and bolster of a railway car underframe, of sheet metal longitudinally corrugated draft arms arranged under and

15 secured to the center sills with inwardly projecting offsets overlapping and secured to the inner sides of said center sills, and a sheet metal reinforcing member extending lengthwise between and attached to said

20 sills provided with a plurality of reinforcing corrugations.

8. The combination with the center sills, end sill and bolster of a railway car underframe, of sheet metal longitudinally corrugated draft arms arranged under and

25 secured to the center sills with inwardly projecting offsets overlapping and secured to the inner sides of said center sills, and a substantially channel shaped reinforcing

30 member extending lengthwise between said center sills and provided with a plurality of longitudinal corrugations.

9. The combination with the wood center

sills of a railway car, of a reinforcing structure arranged between and secured to 35 said sills comprising superposed pressed steel sheets provided with a plurality of longitudinal corrugations.

10. The combination with the wood center sills of a railway car, of a reinforcing 40 structure arranged between and secured to said sills comprising superposed pressed steel sheets provided with a plurality of longitudinal corrugations, and a pressed steel longitudinally corrugated draft arm 45 secured to said sills and reinforcing structure.

11. The combination with the wood center sills of a railway car, of a sheet metal reinforcing element formed with rigidifying 50 corrugations and extending longitudinally of and secured to said center sills, and metal draft arms secured to said reinforcing element and center sills.

12. In combination with the center sills, 55 end sill and bolster of a railway car underframe, sheet metal corrugated draft arms arranged under and secured to the center sills with inwardly projecting offsets overlapping and secured to the inner sides of 60 said center sills, and a pressed metal inverted channel-shaped reinforcing member extending lengthwise between said center sills and provided with a plurality of longitudinal corrugations.

WALTER P. MURPHY.
